UNITED STATES PATENT OFFICE.

CLARENCE A. CEDERLEAF, OF KANSAS CITY, MISSOURI, ASSIGNOR TO IRVING-PITT MANUFACTURING COMPANY, OF KANSAS CITY, MISSOURI, A CORPORATION OF MISSOURI.

VISIBLE-SHEET BINDER.

Application filed May 21, 1927. Serial No. 193,245.

This invention relates to loose leaf binders and has for its primary object the provision of a binder especially adapted for use in the filing of a plurality of overlapping sheets in such a manner that they may be offset to expose a predetermined margin along the upper or lower edges.

One of the objects of the instant invention is to provide a binder metal which includes a plurality of toggle plate units, all operatively supported by the single spring plate, in such a manner that any one of the units may be opened or closed without interference and without imparting movement to the unit next adjoining.

Another object of this invention is to provide friction-reducing and spacing elements which may be interposed between successive toggle plate units of the binder to insure proper opening or closing of any one unit and to further insure the equal spacing apart of the many ring-forming and sheet-holding hooks carried by the independently operable toggle plate units.

It is a recognized fact in the art that it is desirable to bind a large number of overlapping sheets in one device and to provide in that device means whereby one or more of the sheets may be removed without disturbing the remaining sheets and without having to operate all of the sheet-holding members of the binder. Accordingly this invention provides mechanism fulfilling the above objects and shown in one of its forms in the accompanying drawing wherein:

Figure 1 is a face view of a loose leaf binder made in accordance with this invention.

Fig. 2 is a fragmentary face view of the metal part of the binder showing by broken lines one toggle plate unit in the open position.

Fig. 3 is an enlarged cross section taken on line III—III of Fig. 2, and,

Fig. 4 is an enlarged perspective view, showing one end of a toggle plate unit operatively supported by the arcuate spring back.

Similar reference characters designate like parts throughout the several views and the numerals 5 and 6 designate the two covers of the loose leaf binder which are joined by the ordinary flexible back 7 to which may be affixed the metal part of the binder which essentially includes the arcuate back spring 8

having an inturned flange 9 along each edge thereof. This arcuate spring back 8 extends substantially the full length of the binder back 7 and to properly fulfill the requirements of a visible sheet-carrying member must support a plurality of sheet-holding hooks, all of which must be equally spaced apart throughout the length of the back spring. To carry out this invention a plurality of toggle-plate units 10 are provided each of which comprises a pair of plates 12 articulated, along their inner and adjacent edges by any suitable means 13, and engaged, along the remote or outer edges by the flange 9, as clearly shown in Figs. 3 and 4.

As illustrated in Fig. 2 the toggle-plate units 10 extend the entire length of spring 8 and the ends of plates 12 are substantially in abutting relation. To insure that the movement of an intermediate unit will not impart action to the units next adjoining, means has been provided to reduce the friction between adjacent units which means is also utilized as a spacing element to hold the units 10 in the properly spaced relation and to further maintain all of the hooks 14 the proper distance apart. As is customary, the sheet-holding rings are made up of a pair of hooks 14 as shown in Fig. 2.

There are a plurality of these hooks 14 carried by each plate 12. The means for eliminating friction and for holding the various units in the properly spaced relation has here been shown to be a longitudinally extending lug 15 which projects from each end of each plate 12 to present a friction face comparatively small in area with respect to the whole end of its supporting plate 12. It may be possible to eliminate the lug on one end of each plate as the immediately adjoining plate carries a lug 15 but the preferred embodiment of the invention provides that these lugs 15 shall engage as shown in Fig. 2.

Obviously these lugs 15 may be made longer or shorter to space the end hooks 14 apart the required distance. Any one of the toggle units 10 may be opened without disturbing the others and any one of sheets 16 may be removed without opening the rings which hold the remaining sheets in the binder.

Fig. 1 shows the well-known sheet 16 which may be used with devices of this character and which has a plurality of perfora-

tions 17 therethrough along a line spaced inwardly and parallel to the edge to be bound.

In the practical operation and manufacture of a loose leaf binder of this character it is desirable to space the sheet-holding hooks 14 a distance apart which is a multiple of the distance between perforations 17 formed through each of the sheets 16 which are to be used in the binder.

A binder made in accordance with this invention is practical, overcomes the objections to all other sheet-holding devices which are extremely difficult to operate, is durable and may be utilized to arrange a large number of sheets in many positions, valuable to the user.

Having thus described the invention what is claimed as new and desired to be secured by Letters Patent is:

1. In a loose leaf binder, a spring base plate and a plurality of toggle plate units operatively supported in end to end relation by said spring plate, each unit having a set of coacting sheet-holding hooks operable independently of the hooks carried by the remaining units, said sheet-holding hooks being equally spaced apart throughout the length of the spring plate whereby a plurality of relatively narrow loose leaves may be retained by said hooks in overlapping relation, the hook sets engaging any leaf being operable independently of the remaining sets to release that leaf only.

2. In a loose leaf binder, a spring base plate and a plurality of toggle plate units operatively supported in end-abutting relation by said spring plate, the abutting ends of said toggle plates having friction-reducing means whereby a single unit may be operated independently of the adjoining units.

3. In a loose leaf binder, a spring base plate having inturned flanges along its edges, a plurality of toggle plate units operatively

supported by said spring plate beneath said flanges to be retained in the open or closed position thereby and combined friction-reducing and spacing elements between adjacent toggle plate units to permit the independent opening or closing of any one unit supported by said spring plate.

4. In a loose leaf binder, a spring base plate, a plurality of toggle plate units operatively supported in longitudinal alinement by said spring plate, combined friction-reducing and spacing elements integral with each toggle plate and in abutting relation and a plurality of ring-forming hooks carried by each plate respectively of each unit, the hooks of all units being equally spaced apart throughout the length of the binder when said spacing elements are in the abutting relation.

5. In a loose leaf binder, a spring base plate, a plurality of toggle plate units each having its plates articulated along the adjacent edges, a longitudinally extending lug integral with each toggle plate at the end thereof and a plurality of ring-forming sheet-holding hooks carried by each toggle plate, the hooks of all toggle plate units being equally spaced when the lugs of each plate included in the binder are in the engaged position relative to those of the next adjoining toggle plates.

6. In a loose leaf binder, a spring base plate, a plurality of toggle plate units carried thereby, ring-forming hooks carried by each toggle plate and friction reducing means operatively interposed between the adjoining ends of all of said toggle plates whereby the hooks on any unit may be operated to the open or closed positions, said hooks being maintained in equally spaced relation throughout the length of said binder.

In testimony whereof, I hereunto affix my signature.

CLARENCE A. CEDERLEAF.
